APPARATUS FOR ELECTROSTATIC SEPARA-
TION OF MATERIAL PARTICLESBasil Horsfield, Florence, Ala., assignor to Ore-
fraction Incorporated, Pittsburgh, Pa., a cor-
poration of Pennsylvania

Application October 24, 1945, Serial No. 624,164

8 Claims. (Cl. 209—131)

1

My invention relates to electrostatic separation of material particles, and the principal object of my invention is to provide new and improved apparatus for electrostatically separating material particles. This application is a division of my co-pending application Serial Number 279,129, filed June 14, 1939, now abandoned.

In the drawing accompanying this specification, and forming a part of this application, I have shown for purposes of illustration, several forms which my invention may assume, and in this drawing:

Figure 1 is a fragmentary side elevation of apparatus embodying the invention.

Figure 2 is a fragmentary cross-sectional view taken on the line 2—2 of Figure 1, and

Figure 3 is a fragmentary cross-sectional view of a detail of another embodiment.

Referring to Figures 1 and 2, the apparatus comprises a vertical, generally oblong rectangular wall 21, carried in any suitable way by support means 20c. The wall 21 has extending laterally therefrom a plurality of vertically spaced longitudinal ribs with upturned free margins, providing a plurality of gutters 143. The gutters 143 are parallel and extend from a particle feed box 139c to a particle discharge box 92c.

The particle feed box 139c extends transversely of the gutters 143 and has a wall 140c which bears against the free margins of the gutters 143. The wall 140c is provided with a slot 141c of desired, suitable width. Particles to be separated are introduced into the open upper end of the feed box 139c. The slot 141c is of such length that particles are fed to all of the gutters 143 through the slot. Except for its open upper end and the slot 141c, the particle feed box 139c is closed. A wall 142c, abutting the right hand side of the feed box 139c and the right hand ends of the gutters 143, as viewed in Figure 1, closes these ends of the gutters.

The particle discharge box 92c extends transversely of the gutters 143 at the discharge end thereof, that is, at the left hand end thereof as viewed in Figure 1. The particle discharge box 92c is closed everywhere except on the side adjacent the discharge ends of the gutters 143, and except for a desired number of spouts 193c. The spouts 193c are located just above respective dividing walls 196c forming chutes which extend upwardly across the discharge box 92c to and flush with the bottom of a respective gutter 143. The construction and arrangement hence is such that particles discharged from the left hand end of a gutter 143 will slide down the respective di-

2

viding wall 196c of the discharge box 92c and out of the respective spout 193c. The bottom wall of the discharge box 92c may be inclined so as to serve as a chute to the lowermost spout 193c. 5 Any desired number of dividing walls 196c and spouts 193c may be used, it being understood that if a dividing wall 196c is removed, the corresponding spout 193c will be plugged.

Electrode means 22c is provided for causing 10 electrostatic action on the particles in the gutters 143. The electrode means 22c is here shown as of plate-type, substantially coextensive with the area of the wall 21, and, accordingly, particles in the gutters 143 will come under the influence of 15 the electrode means 22c as they move in the gutters from the feed box 92c. The electrode means 22c is so positioned that it defines a selected vertical plane spaced from the free margins of the gutters 143. The electrode means 22c is, of 20 course, insulated from the remainder of the apparatus, and it may be adjustably supported in any suitable way.

In order to cause the particles to move in the 25 gutters 143 from the feed end to the discharge end, the right hand end of the gutters 143, as viewed in Figure 1, may be higher than the left hand end, so that the particles will slide from the feed end to the discharge end, or the gutters may be horizontal, and the support means 20c may be 30 reciprocated, in a direction longitudinally of the gutters 143, in such manner that the particles will progress in the gutters from the feed end to the discharge end, or any other suitable way of moving the particles in the gutters may be adopted, 35 and if the particles are moved by reciprocating the support means 20c, the support means may be reciprocated in any suitable manner, for example, by mechanism such as is shown in my prior application 594,829, now Patent 2,392,044.

40 A particle receiving means 91c is provided which, as here shown, is in the form of an upwardly open trough extending longitudinally below the lowermost gutter 143 and of sufficient transverse width to receive particles which, after 45 having been lifted out of any one of the gutters, fall through the free vertical space left between the electrode means 22c and the free margins of the gutters. The trough 91c is here shown as carried by the support means 20c. The trough 50 91c may also be provided with dividing walls 196c and spouts 193c and, if desired, the walls 196c may be removable and/or adjustable, and the spouts 193c may be selectively plugged or left open.

55 The wall 21 and the ribs providing the gutters

143 may, if desired, be made of insulating material of any suitable kind, coated with a desirably electrically conductive layer of any suitable kind, or the gutters may be made of sheet metal to provide gutters 143 as shown in Figure 3. In general, the gutters are made of any suitable material such that particles thereon may acquire an electric charge therefrom, and are otherwise so constructed and arranged that particles of higher electrostatic susceptibility will be lifted out of the gutters when a sufficient difference of electric potential exists between the gutters and the electrode means 22c. It will be obvious that such difference of potential may be applied by conductors (not shown) connecting the gutters 143 (or 145), or the support 20c, to one of the terminals of a high potential source and the electrode means 22c to the other.

The operation of the apparatus is as follows. While particles are moving in the gutters 143 from the feed box 139c toward the discharge box 92c, the electrode means 22c and the gutters 143 are subjected to a predetermined difference of electric potential. Particles of higher electrostatic susceptibility are lifted, by electrostatic action, out of the gutters 143 into the vertically extending space between the electrode means 22c and the gutters and fall downwardly in that space into the trough 91c. Particles so lifted from a gutter 143 soonest will be discharged from a spout 193c, connected to the trough 91c, nearest the feed box 139c, whereas particles lifted later will be discharged from a spout further away from the feed box. Particles not so lifted out of the gutters 143, either because they are insufficiently susceptible or are non-susceptible, progress therein until they are discharged into the discharge box 92c and from thence into and through the respective spouts 193c connected to the discharge box 92c.

For best results, the gutters 143 (or 145) should be vertically spaced sufficiently so that particles in the gutters will be electrostatically shielded as little as possible, in other words, the spacing should be sufficient so that particles in the gutters may be subjected to electrostatic action by the electrode means 22c. I have found that when the gutters are in a common general plane which is substantially vertical, the gutters are sufficiently vertically spaced if the space between adjacent gutters is approximately one and one half times the overall transverse width of a gutter.

From the foregoing it will be apparent to those skilled in the art that each of the illustrated embodiments of the invention provides a new and improved apparatus for separation of material particles, and accordingly, each accomplishes the principal object of the invention. On the other hand, it also will be obvious to those skilled in the art that the illustrated embodiments of the invention may be variously changed and modified, or features thereof, singly or collectively, embodied in other combinations than those illustrated, without departing from the spirit of the invention, or sacrificing all of the advantages thereof, and that accordingly, the disclosure herein is illustrative only, and the invention is not limited thereto.

I claim:

1. Apparatus for separation of material particles, comprising: means, comprising gutter means for supporting the particles, constructed and arranged to cause the particles to progress in one direction in said gutter means; functionally plate-type electrode means positioned to define a

substantially vertical plane spaced horizontally from said gutter means; particle receiving means; said gutter means and said electrode means and said particle receiving means being relatively so positioned that the space left between said electrode means and said gutter means extends freely downwardly into said particle receiving means; and said electrode means and said gutter means being so constructed and arranged that when they are subjected to a sufficient difference of electric potential, particles of higher susceptibility will be lifted, by electrostatic action, out of said gutter means into said vertical space and fall downwardly therein into said particle receiving means.

2. Apparatus for separation of material particles, comprising: means, for supporting the particles, constructed and arranged to cause the particles to progress in one direction, said supporting means comprising a plurality of gutters, for the particles, spaced so as to be at different levels; functionally plate-type electrode means positioned to define a substantially vertical plane spaced horizontally from said gutters; particle receiving means; said gutters and said electrode means and said particle receiving means being relatively so positioned that the space left between said electrode means and said gutters extends freely downwardly into said particle receiving means; and said electrode means and said gutters being so constructed and arranged that when they are subjected to a sufficient difference of electric potential, particles of higher susceptibility will be lifted, by electrostatic action, out of said gutters into said vertical space and fall downwardly therein into said particle receiving means.

3. Apparatus for separation of material particles, comprising: means, for supporting the particles, constructed and arranged to cause the particles to progress in one direction, said supporting means comprising a plurality of gutters, for the particles, spaced so as to be at different levels; particle feed means constructed and arranged to feed particles to all of said gutters; functionally plate-type electrode means positioned to define a substantially vertical plane spaced horizontally from said gutters; particle receiving means; said gutters and said electrode means and said particle receiving means being relatively so positioned that the space left between said electrode means and said gutters extends freely downwardly into said particle receiving means; and said electrode means and said gutters being so constructed and arranged that when they are subjected to a sufficient difference of electric potential, particles of higher susceptibility will be lifted, by electrostatic action, out of said gutters into said vertical space and fall downwardly therein into said particle receiving means.

4. Apparatus for separation of material particles, comprising: means for supporting the particles, comprising a plurality of spaced gutters disposed at different levels, and constructed and arranged to cause the particles to progress longitudinally of said gutters; functionally plate-type electrode means positioned to define a substantially vertical plane spaced horizontally from said gutters; the space between adjacent gutters being sufficient so that particles in said gutters may be subjected to electrostatic action by said electrode means; and said electrode means and said gutters being so constructed and arranged that when they are subjected to a sufficient difference of electric potential, particles of higher susceptibility will be lifted, by electrostatic action, out of

said gutters into the space between said electrode means and said gutters.

5. Apparatus for separation of material particles, comprising: means, for supporting the particles, constructed and arranged to cause the particles to progress in one direction, said supporting means comprising a plurality of gutters, for the particles, disposed in a common substantially vertical general plane and spaced so as to be at different levels; functionally plate-type electrode means positioned to define a substantially vertical plane spaced horizontally from said gutters; the space between adjacent gutters being sufficient so that particles in said gutters may be subjected to electrostatic action by said electrode means; and said electrode means and said gutters being so constructed and arranged that when they are subjected to a sufficient difference of electric potential, particles of higher susceptibility will be lifted, by electrostatic action, out of said gutters into the space between said electrode means and said gutters.

6. Apparatus for separation of material particles, comprising: means, for supporting the particles, constructed and arranged to cause the particles to progress in one direction, said supporting means comprising a plurality of gutters, for the particles, disposed in a common substantially vertical plane and spaced so as to be at different levels; electrode means disposed laterally spaced from said gutters; the space between adjacent gutters being approximately at least one and one half times the width of said gutters; and said electrode means and said gutters being so constructed and arranged that when they are subjected to a sufficient difference of electric potential, particles of higher susceptibility will be lifted, by electrostatic action, out of said gutters into the space between said electrode means and said gutters.

7. Apparatus for separation of material particles, comprising: means, for supporting the particles, constructed and arranged to cause the particles to progress in one direction, said supporting means comprising a plurality of gutters, for the

particles, disposed in a common substantially vertical plane and spaced so as to be at different levels; functionally plate-type electrode means positioned to define a substantially vertical plane spaced horizontally from said gutters; the space between adjacent gutters being approximately at least one and one half times the width of said gutters; and said electrode means and said gutters being so constructed and arranged that when they are subjected to a sufficient difference of electric potential, particles of higher susceptibility will be lifted, by electrostatic action, out of said gutters into the space between said electrode means and said gutters.

10 8. Apparatus for separation of material particles, comprising: means, for supporting the particles, constructed and arranged to cause the particles to progress in one direction, said supporting means comprising a plurality of gutters, for the particles, disposed in a common substantially vertical plane and spaced so as to be at different levels; particle feed means constructed and arranged to feed particles to all of said gutters; functionally plate-type electrode means positioned to define a substantially vertical plane spaced horizontally from said gutters; the space between adjacent gutters being approximately at least one and one half times the width of said gutters; and said electrode means and said gutters being so constructed and arranged that when they are subjected to a sufficient difference of electric potential, particles of higher susceptibility will be lifted, by electrostatic action, out of said gutters into the space between said electrode means and said gutters.

15 9. Apparatus for separation of material particles, comprising: means, for supporting the particles, constructed and arranged to cause the particles to progress in one direction, said supporting means comprising a plurality of gutters, for the particles, disposed in a common substantially vertical plane and spaced so as to be at different levels; particle feed means constructed and arranged to feed particles to all of said gutters; functionally plate-type electrode means positioned to define a substantially vertical plane spaced horizontally from said gutters; the space between adjacent gutters being approximately at least one and one half times the width of said gutters; and said electrode means and said gutters being so constructed and arranged that when they are subjected to a sufficient difference of electric potential, particles of higher susceptibility will be lifted, by electrostatic action, out of said gutters into the space between said electrode means and said gutters.
